CARL MÜLLER, OF NEW YORK, N. Y.

Design No. 2,919, dated February 4, 1868.

DESIGN FOR A STATUETTE.

The Schedule referred to in these Letters Patent and making part of the same.

TO ALL WHOM IT MAY CONCERN:

Be it known that I, CARL MÜLLER, of the city, county, and State of New York, have invented a new and characteristic Design for a Figure and Base; and I do hereby declare that the following is a full, clear, and exact description thereof, which will enable those skilled in the art to make and use the same, reference being had to the accompanying drawings, forming part of this specification, in which—

Figure I is a perspective view of said figure and base, viewing slightly from the right.

This invention relates to a design for a blacksmith in a resting position, leaning against an anvil, whercon his coat is loosely thrown. The blacksmith is in the act of lighting his pipe with a hot crow-bar or iron, as shown in the drawing.

The base accompanying the figure is of a round shape, and on it, about the feet of the blacksmith, are lying a hammer, horse-shoe, nail, &c.

A represents the blacksmith, leaning against the anvil B; C, the base, with the hammer, horse-shoe, &c., d d, on it.

What I claim as new, and desire to secure by Letters Patent, is—

The design for said figure and base, as herein shown and described.
